THRESHER

Albert B. Welty, Moline, Ill., assignor to International Harvester Company, a corporation of New Jersey

Application September 23, 1940, Serial No. 357,919

5 Claims. (Cl. 130—27)

This invention relates to improvements in the construction of the cylinder which is used in harvester threshers.

It is desirable to provide a cylinder for a harvester thresher which is light in weight, but strong enough to withstand severe use.

It is also desirable to have a cylinder which can be readily converted from a rasp bar type into a tooth type or a flail bar type of cylinder.

It is, therefore, an important object of the present invention to provide a cylinder which is lighter in weight than previous cylinders, but which is much stronger and easier to manufacture.

Another object of the invention is to provide a cylinder which may be readily changed from a flail bar cylinder to a rasp bar cylinder or a tooth type of cylinder.

Another object of the present invention is to provide a cylinder which may be easily assembled.

According to the present invention, the cylinder comprises a cylinder shaft on which are mounted cylinder head plates in which a plurality of converging slots are provided. A cylinder bar support having the edges thereof bent downwardly is inserted in the converging slots of the cylinder head plates and is secured thereto by welding. By virtue of this construction an efficient light weight, but much stronger cylinder is provided, which is especially advantageous in small types of harvester threshers. The cylinder is also much easier to assemble and manufacture. These and other objects and advantages of the present invention will be apparent to those skilled in the art after a consideration of the following detailed description of the preferred structural embodiment taken in conjunction with the accompanying drawing.

In the drawing:

Figure 1 is a side view of one of the cylinder head end plates;

Figure 2 is an end view of the center cylinder head plate;

Figure 3 is an end view of one of the cylinder head end plates;

Figure 4 is a side view of the novel assembled cylinder; and,

Figure 5 is an enlarged end view, showing the welds which secure the cylinder bar support to the cylinder head plate.

Referring now to the drawing, and more particularly to Figure 1, there is shown one of the cylinder head end plates 10, which is hexagonal in shape. In each of the sides of the cylinder head plate 10 is provided a pair of reentrant por-

tions or converging recesses 11. The center of the plate 10 is provided with an opening 12, in which is inserted a hub member 12a which is secured thereto by a plurality of rivets 13. A keyway 14 is provided within an opening 12b in the hub member 12a. The center cylinder head plate 15 is shown in Figure 2 and is substantially of the same shape as the end cylinder head plate 10 except that only an opening 15a is provided at the center thereof.

The cylinder head end plates 10 and one of the cylinder head center plates 15 are inserted on a shaft 16 in which there is provided alined keyways 17. The slots in the cylinder head plates 10 and 15 are in alinement. A key 18 is inserted in the keyway 17 in the shaft 16 and the keyway 14 in the hub 12. The key 18 secures the cylinder head end plates 10 to the cylinder shaft 16. After the key 18 has been inserted in the keyways 14 and 17, it is locked therein by a chisel mark in the shaft at the rear of the head portion thereof. The center cylinder head plate 15 is not secured to the cylinder shaft 16.

A plurality of cylinder bar supports in the form of rectangular plates 19 are associated with the cylinder head plates 10 and 15. The cylinder bar support 19 comprises a longitudinal plate member having a flat surface 21, the outer edges of which are bent downwardly, as at 22. The angle of the flanges 22 is substantially the same as the angle of the converging slots 11 in the cylinder head plates 10 and 15. The cylinder bar supports 19 are inserted in the converging recesses 11 of the cylinder head plates 10 and 15, as shown in Figure 5. It is to be noted from Figure 5 that, when the cylinder bar supports 19 are inserted in the slots 11, the outer edge of each of the flanges 22 contact the outer edge of the slots 11, and the inner portion of flat surface 21 contacts the flat portion of the cylinder head plates 10 and 15 between the slots 11. In this way the cylinder bar supports 19 are held in position with respect to the cylinder head plates 10 and 15. After the cylinder bar supports 19 have been inserted in the alined recesses 11 in the cylinder head end plates 10 and the cylinder head center plate 15, the outer edge of the flanges 22 are welded to the cylinder head plates 10 and 15, as at 23; and the inner surface of the flat portion 21 is welded to the cylinder head plates 10 and 15, as at 24. Only a minimum amount of welding need be applied to the cylinder bar support 19 and the cylinder head end plates 10 and 15, since it need only hold the cylinder bar sup-

port 19 against lateral movement with respect to the cylinder head plates 10 and 15.

On the flat surface 21 of the cylinder bar support 19 may be secured any preferred type of threshing means. As shown in Figure 5, a rasp bar 25 is secured to the flat surface 21 in which are provided a plurality of openings 26. A bolt 27 is inserted in suitable openings provided in the rasp bar 25 and the openings 26 in the cylinder bar support 19. A nut 28 is provided on the bolt 27 so as to secure the rasp bar 25 to the flat surface 21. While the rasp bar has been shown attached to the cylinder bar support 19, it is to be understood that any type of threshing means may be secured thereto, such as a flail bar or tooth bar.

From the foregoing description it should be apparent that a novel cylinder construction has been provided. The cylinder is light in weight, yet exceptionally strong and easy to manufacture. The design is such that the cylinder bar support can be secured to the cylinder head plates with a minimum of welding. The end plates are simple to manufacture, since they can be shaped by a single punching operation, and the cylinder bar supports can likewise be prepared by a single punching and bending operation. The cylinder bar 19 is supported intermediate the cylinder head end plates 10 by the center cylinder head plate 15 which is welded 30 to the cylinder bar support 19 in the same manner as the cylinder head end plates 10.

While only the preferred structural embodiment of the present invention has been shown, it is to be understood that the invention is not to be limited to the specific details shown and described, but that widely different means may be employed in the practice of the broader aspects of my invention.

What is claimed is:

1. A cylinder construction comprising a shaft, a plurality of plates secured to the shaft at spaced points, the outer periphery of the plates having a plurality of pairs of converging recesses formed therein, and a plurality of bars each having a pair of flanges adapted to engage the recesses in said plates in such a manner that the outer edge of the flanges contacts the outer edge

of the recess and the inner portion of the bars contacts the portion of the plate between the recesses, and said bars being secured to said plates by welding at their points of contact.

5. 2. A cylinder construction for threshers comprising a shaft, a plurality of hexagonal shaped plates secured at spaced points to the shaft, said plates having a pair of outwardly converging recesses provided in each side thereof, cylinder bars having a pair of flanges inserted in the recesses in such a manner that the outer edge of each flange contacts the outer edge of the recesses and the inner portions of the cylinder bars contact the portion of the plates between the recesses, and means for securing the cylinder bars to the plates.

3. A cylinder construction for threshers comprising a shaft, a plurality of hexagonal shaped plates secured at spaced points to the shaft, said plates having a pair of converging recesses provided in each side thereof, and cylinder bars having a pair of flanges inserted in the recesses in such a manner that the outer edge of each flange contacts the outer edge of the recesses and the inner portion of the cylinder bars between the flanges contacts the portion of the plates between the recesses, and said cylinder being secured at their points of contact with the plate by welding.

4. In combination, a shaft, a pair of hexagonal shaped end plates secured on the shaft, hexagonal shaped plates positioned on the shaft intermediate the end plates, said plates having a pair of outwardly converging recesses provided in each of the sides thereof, and bars having a pair of downwardly extending flanges inserted in the recesses in the plates and being secured thereto by welding.

5. In combination, a shaft, a plurality of polygonal shaped plates secured at spaced points to the shaft and having a pair of outwardly converging recesses provided in each of the sides thereof, bars having downwardly extending flanges inserted in the recesses in the plates and being welded to the plates, and threshing means secured on said bars.

ALBERT B. WELTY.
